UNITED STATES PATENT OFFICE

172,450

SINK MAT

William D. Timmons, Coshocton, Ohio

Application May 27, 1953, Serial No. 25,212

Term of patent 14 years

(Cl. D9—6)

To all whom it may concern:

Be it known that I, William D. Timmons, have invented a new, original, and ornamental Design for Sink Mats, of which the following is a specification, reference being had to the accompanying drawing, forming a part hereof.

Fig. 1 is a top plan view of a sink mat showing my new design.

Fig. 2 is a bottom plan view of the same.

Fig. 3 is a cross sectional view of the mat taken along line 3—3 of Fig. 1 in the direction of the arrows.

Fig. 4 is a cross sectional view thereof, taken along line 4—4 of Fig. 1, in the direction of the arrows.

I claim:

The ornamental design for a sink mat, substantially as shown.
